UNITED STATES PATENT OFFICE

110,820

DESIGN FOR A WATCH BRACELET OR THE LIKE

La Roy E. Pitman and Lawrence P. Keeler, Attleboro, Mass., assignors to Pitman & Keeler, a partnership composed of La Roy E. Pitman and Lawrence P. Keeler, Attleboro, Mass.

Application June 1, 1938, Serial No. 77,480

Term of patent 7 years

To all whom it may concern:

Be it known that we, La Roy E. Pitman and Lawrence P. Keeler, citizens of the United States, residing in the city of Attleboro, county of Bristol, and Commonwealth of Massachusetts, have invented a new, original, and ornamental Design for a Watch Bracelet or the like, of which the following is a specification, reference being had to the accompanying drawing, forming a part thereof.

Fig. 1 is a plan view of a watch bracelet showing our new design;

Fig. 2 is an edge view of the same; and

Fig. 3 is a bottom plan view of the watch bracelet.

We claim:

The ornamental design for a watch bracelet or the like, substantially as shown.

LA ROY E. PITMAN.
LAWRENCE P. KEELER.
